UNITED STATES PATENT OFFICE.

THOMAS P. FORD, OF NEW YORK, N. Y.

HOSE-SUPPORTER.

1,144,832.

Specification of Letters Patent. Patented June 29, 1915.

Application filed May 13, 1914. Serial No. 838,295.

To all whom it may concern:

Be it known that I, THOMAS P. FORD, a citizen of the United States, and a resident of the city of New York, borough of Brooklyn, in the county of Kings and State of New York, have invented a new and Improved Hose-Supporter, of which the following is a full, clear, and exact description.

The object of the present invention is to provide a new and improved hose supporter which is very simple and durable in construction and arranged to permit the user to conveniently and quickly engage the hose material with the supporter and to readily 15 adjust the parts to securely hold the hose material in place without danger of tearing it.

In order to accomplish the desired result use is made of a frame and a clasp, one movable on the other, the frame having a bottom bar and a clasp having two clamping bars adapted to bear on opposite sides of the frame bar to clamp the hose material between the said frame bar and the said clasp bars.

25 A practical embodiment of the invention is represented in the accompanying drawings forming a part of this specification, in which similar characters of reference indicate corresponding parts in all the views.

30 Figure 1 is an enlarged cross section of the hose supporter with the parts in open position; Fig. 2 is a front elevation of the same; Fig. 3 is a cross section of the same with the parts in closed position; Fig. 4 is 35 a front elevation of the same; Fig. 5 is a fragmentary front elevation of a modified form of the hose supporter with the parts in open position; Fig. 6 is a cross section of the same; and Fig. 7 is a like view of the 40 same with the parts in closed position.

The hose supporter consists essentially of an open frame A and a clasp B, both preferably made of wire. The frame A consists of a bottom bar A' terminating in side bars A² 45 which terminate at their upper ends in short top bars A³ terminating in a loop A⁴ which extends upwardly and is engaged by a tape, strap or like supporting member C. The clasp B consists of two bottom or clamping members B' and B², normally overlying one 50 the other, as plainly indicated in Fig. 1, and the said bottom or clamping bars B' and B² are of a length somewhat less than that of the frame bottom bar A'. The clasp bottom 55 or clamping bars B' and B² terminate in upwardly and inwardly inclined side bars B³,

B³ and B⁴, B⁴ which terminate at their upper ends in top bars B⁵, B⁵ and B⁶, B⁶ formed at their outer ends into loops B⁷ 60 slidingly engaging the side bars B² of the frame A.

When the clasp B is in lowermost position on the frame A, as shown in Figs. 1 and 2, then the bottom or clamping bars B' and B² and the lower portions of the side bars B³, B⁴ 65 extend in front of the frame A, and the clasp bottom bars B', B² are a distance below the frame bottom bar A' to provide an opening for the passage of the material D of the hose, as plainly indicated in Figs. 1 and 2. The user now slides the clasp B upward and when the top bars B⁵, B⁶ of the clasp B reach the top bars A³ of the frame 70 then a slight upward and transverse pressure causes the clasp B to assume the position shown in Figs. 3 and 4 whereby the bottom or clamping bars B', B² are moved to opposite sides of the frame bottom bar A' to clamp the hose material between the three parts A', B' and B², as plainly indicated in 75 Figs. 3 and 4. It will be noticed that the upward pressure referred to places the clasp B under tension owing to the top bars B⁵, B⁶ abutting against the frame top bars A³, thus causing the bars B', B² to firmly clamp 80 the material in position on the frame bar A'. 85

When it is desired to release the hose, the user presses against the side bars B⁴, B⁴ in a forward and slightly upward direction to disengage the bottom bars B', B² from the 90 bottom bar A', thus releasing the material and allowing the clasp B to slide downward into open position.

It will also be noticed that a large clamping surface is provided between the bottom 95 bar A' and the bottom or clamping bars B', B², so that the hose material is not liable to be torn when the hose is subjected to strain.

The hose supporter shown in Figs. 5, 6 and 7 consists of a frame F and a clasp G, 100 of which the frame F is provided at its bottom bar F' with an offset F², on which the hose material is clamped by the two clamping bars G', G² of the clasp G. The eyes G³, G⁴ of the side arms G⁵, G⁶ are mounted to 105 swing on the bottom bar F' adjacent the offset F², so that when the clasp G is in lowermost position, as shown in Fig. 5, sufficient space is had between the offset F² and the clamping bars G', G² for the passage of the 110 hose material. The clasp G is swung upward to engage the bars G', G² with op-

posite sides of the offset F^2 to clamp the hose material between the said bars F^2 , G' and G^2 , as shown in Fig. 7. The clamping action in this case is the same as above described relatively to the form shown in Figs. 1, 2 3 and 4.

The hose supporter shown and described is very simple in construction and effectively clamps the hose material in position.

Having thus described my invention, I claim as new and desire to secure by Letters Patent:

1. A hose supporter, comprising a frame having a bottom bar, and a clasp movable on the said frame and provided with two clamping bars, the clasp being of a size to lie within the frame and when in lowermost position providing a space for the entrance of the hose material between the frame bottom bar and the said clasp clamping bars, the clasp when in raised position lying within the frame and having its clamping bars located on opposite sides of the frame bottom bar to clamp the hose material between the frame bar and the said clasp clamping bars.

2. A hose supporter, comprising a frame having a bottom bar, and a clasp movable on the said frame and provided with two straight clamping bars of a length less than the frame bottom bar, the clamping bars of the clasp when in lowermost position being a distance below the frame bottom bar to provide a space for the entrance of the hose material between the said bars and the clasp when in raised position extending within the frame opening and having its clamping bars located on opposite sides of the frame bottom bar to clamp the hose material between the frame bar and the said clasp bars.

3. A hose supporter, comprising an open rectangular frame and a clasp, and the said clasp having a pair of bottom bars, one in front of the other and of a length less than that of the frame bottom bar, the said clasp bottom bars terminating in upwardly extending side bars inclined toward each other, the side bars terminating in horizontal top members having eyes slidably engaging the said frame side bars.

4. A hose supporter, comprising an open frame and a clasp, the open frame having a bottom bar, side bars and a top bar having its central portion bent outwardly to form

an upwardly extending top loop, and the 55 said clasp having a pair of bottom bars one in front of the other and of a length less than that of the frame bottom bar, the said clasp bottom bars terminating in upwardly extending side bars inclined toward each 60 other, the side bars terminating in top members having eyes slidably engaging the said frame side bars, the said top members of the clasp when the latter is in clamping relation to the bottom bar of the frame abutting against the top bar and the said clasp bottom bars engaging opposite sides of the frame bottom bar.

5. A hose supporter, comprising a rectangular frame, and a clasp having a 70 straight bottom bar of less length than the bottom bar of the frame, upwardly and inwardly inclined side bars extending from the ends of the bottom bar, and outwardly projecting top bars extending from the ends 75 of the inclined bars and terminating in eyes slidably engaging the sides of the frame, whereby the clasp will be of such a size as to lie entirely within the frame and when in clamping position its top bars will be in 80 engagement with the top bar of the frame and its bottom bar will be in engagement throughout its length with the bottom bar of the said frame.

6. A hose supporter, comprising an open 85 frame, and a clasp having a pair of clamping bars, pairs of upwardly and inwardly inclined side bars, and pairs of top bars terminating in eyes slidably engaging the sides 90 of the frame, the clamping bars lying on opposite sides of the bottom bar of the frame when in clamping position.

7. A hose supporter comprising an open 95 rectangular frame, and a clasp having a pair of straight parallel clamping bars of less length than the bottom bar of the frame, pairs of upwardly and inwardly inclined side bars and pairs of top bars terminating in eyes slidably engaging the sides of the frame.

In testimony whereof I have signed my name to this specification in the presence of two subscribing witnesses.

THOMAS P. FORD.
